United States Patent Office

Des. 189,390
Patented Nov. 29, 1960

189,390

BODY MASSAGER

Thomas D. Tweedie, Monrovia, Calif., assignor to R. A. Fischer & Co., Glendale, Calif., a partnership

Filed Jan. 19, 1960, Ser. No. 59,101

Term of patent 14 years

(Cl. D83—1)

Fig. 1 is a front perspective view taken from the right side of a body massager showing my new design;
Fig. 2 is a rear elevational view thereof;
Fig. 3 is a top plan view thereof;
Fig. 4 is a left side elevational view thereof; and
Fig. 5 is a bottom plan view thereof.

I claim:

The ornamental design for a body massager, substantially as shown.
